(57) **CLAIM**

The ornamental design for cart, as shown and described.

DESCRIPTION

FIG. 1 is a perspective view of a cart according to my new design;

FIG. 2 is a front elevation view thereof,

FIG. 3 is a rear elevation view thereof,

FIG. 4 is a left side elevation view thereof, the right side view being a mirror image thereof;

FIG. 5 is a top plan view thereof; and,

FIG. 6 is a bottom plan view thereof.

The elements shown in broken line are included for the purpose of illustrating environment and form no part of the claimed design.

1 Claim, 3 Drawing Sheets

FIG. 1

FIG. 2

FIG. 3

FIG. 4

FIG. 5

FIG. 6
